UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,090, dated September 22, 1896.

Application filed August 5, 1896. Serial No. 601,825. Term of patent 3½ years.

To all whom it may concern:

Be it known that I, CHARLES Booz, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of a series of scroll ornaments arranged at regular distances apart with small diamonds forming a background for said ornaments, as represented in the accompanying drawing.

15 The border for said design is also formed of similar scroll ornaments with interlacing scrolls and small diamonds forming a background for said ornaments, as shown.

What I claim is—

1. The design for wall-paper herein shown 20 and described.

2. In the design for wall-paper the border herein shown and described.

Witness my hand this 1st day of August, 1896.

CHARLES BOOZ.
